UNITED STATES PATENT OFFICE.

WILLIAM P. DAY, OF CLEVELAND HEIGHTS, OHIO.

RAIL SUPPORT.

Application filed July 13, 1927. Serial No. 205,340.

This invention relates to certain new and useful improvements in composite railroad stringers and ties and more particularly to cross ties of the insulated type.

5 The main object of the invention is to provide a simple, efficient and durable rail support which comprises few parts which are so interlocked with each other as to impart great strength and rigidity to the entire structure.

10 Another object of the invention is to provide a generally improved cross tie construction of the character described which is made up of a steel skeleton frame, the several parts 15 of which are made of standard materials capable of being produced at any properly equipped steel mill, and so constructed that the tie may be put together, either at the mill or at the track side and the concrete filling 20 placed in position after the skeleton structure of the tie has been put in place.

Another object of the invention is to provide a cross tie construction which will not become buckled or broken as a result of heavy 25 loads passing over the rails and which will not become "center bound".

A still further and important object of the invention is to provide a cross tie construction wherein a maximum support is given to each 30 rail and lateral deflection of the rails is prevented and in which the two rails are allowed a limited up and down movement independent of each other.

Further and more limited objects of the 35 invention will appear as the description proceeds and by reference to the accompanying drawing in which Fig. 1 is a top plan view of my improved tie with the rails secured thereto; Fig. 2 is a vertical sectional view on the line 2—2 of Fig. 1; Fig. 3 is a vertical sectional view on the line 3—3 of Fig. 1; Fig. 4 is a vertical sectional view on the line 4—4 of Fig. 1; Fig. 5 is a perspective view of one of the blocks to which the rails are secured; Fig. 6 is a top plan view of the skeleton frame assembled; and Fig. 7 is a view in side elevation of the skeleton frame.

50 Referring now to the drawing in which like parts are referred to by the same reference characters, the numerals 1, 2, 3 and 4 designate plates which form a part of the skeleton frame and which are shaped as shown most clearly in Figs. 4, 6 and 7. These plates are 55 preferably made of steel and have portions 5 cut out therefrom and bent as shown most

clearly in Figs. 4, 6 and 7, the purpose of which will hereinafter appear. The plates 1, 2, 3 and 4 are secured together and held in spaced relation with respect to each other by means of spaced, parallel, transversely extending cross beams 6 which extend through slots in the opposite ends of the plates 1, 2, 3 and 4. The cross beams are preferably channel shaped in section and welded to the plates so as to hold the same against displacement. 60 It will also be seen that the outer plates 1 and 4 are slightly inclined so that water will be drained off and away from the tie. This inclination of the outer plates also serves to strengthen that portion of the tie on which the 70 rails rest.

By an inspection of Figs. 1 and 2, it will be seen that the plates are so spaced that the distance between the plates 2 and 3 is greater than the distance between the plates 1 and 2 75 or 3 and 4. The skeleton frame when assembled appears as shown most clearly in Figs. 6 and 7. The skeleton frame is placed in a form and concrete is poured in to fill the spaces between and adjacent the plates. The 80 bent portions 5 interlock with the concrete and serve to reinforce and strengthen the entire structure. Before the concrete is poured wedge shaped blocks are positioned between the plates 2 and 3 and spaced apart. 85 These blocks serve to provide a pair of wedge shaped openings 7 and 8 on each side of the completed cross tie. When the concrete has hardened and set, the form and the blocks are removed. Wedge shaped blocks 9 and 10, one of which is shown in detail in Fig. 5, are then positioned within the opening 7 and 8. These blocks 9 and 10 fit neatly within the openings 7 and 8 as shown in Fig. 3 and rest loosely therein. The tie plates 11 90 rest on the top of blocks 9 and 10 and the rails 13 and 14 are fastened to the blocks by means of spikes 15 which extend through the tie plates and into the wooden blocks. It will thus be seen that the rails may have an 95 up and down movement independent of each other and that there will be no lateral deflection of the rails. It will also be clear that due to the shape of the openings and blocks the strain will be equally distributed 100 over a comparatively large area.

The skeleton frame may be shipped in a disassembled or knocked down condition and may be assembled at the track side. The bottom edges of the completed tie are inclined 110

upward slightly as shown in Figs. 2 and 4. This inclination of the outer edges of the tie permits the ballast *b* to be readily tamped around and under the tie.

5. It will be clear that I have provided a tie or rail support which accomplishes the objects of the invention as hereinbefore stated. Various changes may be made in the details of my construction without departing from 10 the spirit of my invention. For example, the blocks 9 and 10 may be made of metal or reinforced concrete, instead of wood, and the flanges 1, 2, 3 and 4 as well as the cross beam 6 may be of different shape. I therefore wish 15 my invention to be limited only in accordance with the scope of the appended claims.

Having thus described my invention, what I claim is:—

1. A rail support of the character described comprising a plurality of spaced parallel plates extending parallel with the track, parallel cross beams extending transversely of the track and connecting said plates and holding the same in spaced relation, concrete filling the spaces between said plates, bearing blocks disposed between two of said plates and resting loosely therebetween, a tie plate carried by each of said bearing blocks and means for fastening a rail 30 to said bearing blocks.

2. A rail support of the character described comprising a plurality of spaced parallel plates extending parallel with the track, cross beams extending transversely of 35 the track and connecting said plates and holding the same in spaced relation, concrete filling the spaces between certain of said plates, a plurality of bearing blocks resting loosely in the concrete and means for fastening a rail to said bearing blocks.

40 3. A cross tie of the character described comprising a skeleton frame consisting of a pair of transversely extending cross beams, a plurality of end members spaced apart and secured to said cross beams adjacent the ends thereof and extending at right angles thereto, said cross beams extending through said end members and holding the same in spaced relation, concrete filling the space between 45 said end members and forming a composite block at each end of the cross tie, the upper face of each composite block having one or more wedge shaped openings therein, wedge shaped blocks resting loosely in said openings, and means for securing a rail to each of 50 said wedge shaped blocks.

4. A rail support of the class described comprising a metallic skeleton frame including parallel cross beams, a plurality of 60 plates connecting the ends of said cross beams and being spaced apart and forming a cross tie, concrete filling the space between said plates at each end of the tie, the ends of said tie having a plurality of wedge shaped 65 openings in the upper face thereof, wedge

shaped blocks resting loosely in said openings and means for securing a rail to said wedge shaped blocks.

5. A rail support of the character described comprising a demountable skeleton frame including a plurality of plates each having openings in the opposite ends thereof, cross beams connecting said plates and extending through the openings therein and holding the same in spaced relation, each of said plates having portions cut out and bent outwardly from the surface thereof, a plurality of bearing blocks disposed between certain of said plates, concrete filling the space between said plates and bearing blocks and means for securing a rail to each of said bearing blocks, said bearing blocks resting loosely between said plates.

6. A rail support of the character described comprising a plurality of spaced plates extending substantially parallel with the track, cross beams extending transversely of the track and connecting said plates and holding the same in spaced relation, concrete filling the spaces between said plates, rail supporting blocks disposed between certain of said plates, a tie plate carried by each of said rail bearing blocks, and means for fastening the rail thereto.

7. A rail support of the character described comprising a plurality of spaced plates extending substantially parallel with the track, cross beams extending transversely of the track and connecting said plates and holding the same in spaced relation, concrete filling the spaces between certain of said plates and a plurality of rail supporting blocks resting in the concrete and means for fastening a rail to said blocks.

8. A cross tie of the character described comprising a skeleton frame consisting of a pair of transversely extending cross beams, a plurality of end members spaced apart and secured to said cross beams adjacent the ends thereof, said cross beams connecting said end members and holding the same in spaced relation, concrete filling the space between said end members and forming a composite block at each end of the cross tie, the upper face of each composite block having one or more openings therein and rail blocks arranged within said openings, and means for securing a rail to said rail blocks.

9. A rail support of the class described comprising a metallic skeleton frame including cross beams, a plurality of plates connecting the ends of said cross beams and being spaced apart and forming a cross tie, concrete filling the space between said plates at each end of the tie, the ends of said tie having a plurality of openings in the upper face thereof, rail blocks arranged within said openings and means for securing a rail thereto.

10. A rail support of the character de-

scribed comprising a demountable skeleton frame including a plurality of plates having openings in the opposite ends thereof, cross beams connecting said plates and extending through said openings and holding the plates in spaced relation, a plurality of rail bearing blocks disposed between certain of said plates, concrete filling the space between said plates and bearing blocks and means for securing the rail to said bearing blocks.

11. A rail support as set forth in claim 10 in which said plates have portions cut out and bent upwardly therefrom whereby to reinforce and strengthen the support as a whole.

12. A rail support of the character set forth comprising a demountable skeleton frame including a plurality of plates assem-

bled to form composite blocks, bars connecting said composite blocks and holding the same in spaced relation, each of said composite blocks having one or more openings in the upper face thereof, rail blocks arranged within said openings and movable freely in a vertical plane independent of each other and means for securing a rail to each of said rail blocks.

13. A rail support as set forth in claim 12 in which the openings in the upper face of said composite blocks are substantially wedge shaped and said rail blocks are similarly shaped.

In testimony whereof, I hereunto affix my signature.

WILLIAM P. DAY.
